(57) **CLAIM**

The ornamental design for a light as shown and described.

DESCRIPTION

FIG. 1 is a top perspective view of a light, showing our new design.

FIG. 2 is a bottom perspective view thereof.

FIG. 3 is a top view thereof.

FIG. 4 is a bottom view thereof.

FIG. 5 is a front view thereof.

FIG. 6 is a rear view thereof.

FIG. 7 is a right-side view thereof; and,

FIG. 8 is a left-side view thereof.

Portions of the light are shown in broken lines. Portions shown in broken lines form no part of the claimed design. Portions of the light are shown with jagged broken lines which define an indeterminate length. The jagged broken lines form no part of the claimed design.

1 Claim, 8 Drawing Sheets
